UNITED STATES PATENT OFFICE.

CHARLES HERBERT OCUMPAUGH, OF ROCHESTER, NEW YORK.

DESIGN FOR A BICYCLE-FRAME.

SPECIFICATION forming part of Design No. 28,873, dated June 14, 1898.

Application filed April 29, 1898. Serial No. 679,245. Term of patent 14 years.

To all whom it may concern:

Be it known that I, CHARLES HERBERT OCUMPAUGH, a citizen of the United States, residing at Rochester, in the county of Monroe and State of New York, have invented and produced a new and original Design for Bicycle-Frames, of which the following is a specification, reference being had to the accompanying drawing, forming part thereof.

In the accompanying drawing the figure is a perspective view of a bicycle-frame, showing the new design.

As shown in the drawing, the leading or material feature of my design consists of the members 1 and 2, joined to curved wheel-cases 4 and 5, the latter being joined to other frame members.

6 denotes a hanger, and 7 and 8 members of the main fork.

9 indicates a lower frame-bar. 20

The wheel-cases and members 1 and 2 are situated in the same plane. Said cases form ornamental connections for the rod-like frame members, it being understood that the frame members 6 and 8 are connected directly to the 25 respective cases.

Having described my invention, what I claim as new, and desire to secure by Letters Patent, is—

The design for a bicycle-frame, as herein 30 shown and described.

CHARLES HERBERT OCUMPAUGH.
